UNITED STATES PATENT OFFICE.

GEORGE BIBLE, OF CHICAGO, ILLINOIS.

SMOKE-SHADE HANGER.

No. 927,933.

Specification of Letters Patent.

Patented July 13, 1909.

Application filed February 19, 1908. Serial No. 416,687.

To all whom it may concern:

Be it known that I, GEORGE BIBLE, a citizen of the United States, residing in Chicago, in the county of Cook and State of Illinois, have invented certain new and useful Improvements in Smoke-Shade Hangers, of which the following is a description.

My invention belongs to that class of devices known as smoke shade hangers or the like, and particularly an adjustable hanger, and has for its objects the production of a simple, efficient and satisfactory hanger at a comparatively small cost.

To this end, my invention consists in the novel construction, arrangement and combination of parts herein shown and described and more particularly pointed out in the claim.

In the drawings wherein like reference characters indicate like or corresponding parts, Figure 1, is a view in elevation of my device showing the same positioned on a chandelier. Fig. 2, is a perspective view of the device. Fig. 3, is a sectional view taken substantially on line 3—3 of Fig. 2. Fig. 4, is a sectional view taken substantially on line 4—4 of Fig. 1. Fig. 5, is a view in elevation of the clip showing a modification in construction. Fig. 6, is a sectional view of the same taken substantially on line 6—6 of Fig. 5. Fig. 7, is a partial sectional view of another modified form of my device, and, Fig. 8, is a view in elevation showing a satisfactory arrangement of the clips when it is desired to use two hangers.

Referring to the drawings, 1 is a chandelier provided with one or more burners 2, the smoke shade 9 being supported above the burner by means of my improved smoke shade hanger.

My preferred form of device comprises a resilient chandelier engaging clip 3 and an arm or hanger 6 secured thereto. As shown the arm or hanger is preferably provided with an extension 7 which is made adjustable relatively to the arm 6 and supports the shade 9 by means of a chain 8 or its equivalent. The clip 3 is extended on the sides as at 4—4 so that it is adapted to engage the drop pipe 1 of the chandelier so that the same may be easily positioned or removed from the chandelier 1. The arm 6 is secured to the clip in any suitable or preferred way. An extension or bracing part 5 is provided on the lower part of the clip 3 to form a brace for the device. As shown in Fig. 2,

the extended arm 7 preferably telescopes within the arm 6 so that the shade may be horizontally adjusted over the burner 2. The arm 6 is preferably made of sheet metal and rolled into a tube being split or slightly open at the edges as shown at 14 so that the resiliency of the tube or metal sheet of the arm 6 will in itself secure the adjustable part or extension 7 in the desired position. If desired, the clip may be extended similar to 4—4 on the extended part 5. However, the same is unnecessary.

As shown in Figs. 5 and 6, the arm 6 is made solid, that is, of a piece of tubing without the split or opening 14, and is secured to the clip 3 by turning over the end or upsetting the same as shown at 10 and providing a suitable collar 11 as shown; same may be also soldered if desired. 75

In the form shown in Fig. 7, the arm 6 may be in the form of a tube and provided with a slot 15 cut therein or made of sheet metal and formed into a tube with an opening similar to 14 as shown in Fig. 2. A small screw or its equivalent is provided adapted to pass through the slot 15 and engage the extension 7, the head of the screw thus securely locking the extended part 7 in the desired position. Any other suitable means for locking part 7 in the desired position may be employed. As shown in this figure, braces 12—12 are preferably provided, it being obvious that one or the other may be omitted. 90

Fig. 8 shows the application of two clips and hanger bars to the chandelier so that the shade may be supported at both sides of the chandelier, one of the clips being preferably turned down at the extended portion of 95 5 as shown at 5¹ so that it braces its respective arm. While only two clips are shown positioned together, it is obvious that there may be more than two arranged similarly, or that others may be arranged at other 100 points on the chandelier. The preferred style of clip shown permits the arrangement of a plurality of clips whether two or more substantially as shown in Fig. 8, whereas, if the clip is not constructed substantially 105 as shown, the number would probably be limited to two.

Having thus described my invention, it is obvious that various immaterial modifications may be made in the form, arrangement and combination of parts herein shown and described without departing from the 110

spirit of my invention; hence I do not wish to be understood as limiting myself to the exact construction and arrangement shown.

What I claim and desire to secure by Letters-Patent is:

In a device of the character described, the combination with a horizontally disposed supporting arm of a clip rigidly connected to said supporting arm, said clip being formed of an integral piece of metal and comprising an elongated front portion which extends both above and below the plane of the supporting arm and rearwardly directed curved members adapted to embrace a vertical support, said members lying above the

plane of the supporting arm, substantially as shown and described both the upwardly and downwardly extending parts of the front portion lying in the same vertical plane whereby said front portion is adapted to bear against said vertical support throughout its length.

In testimony whereof, I have signed my name in the presence of two subscribing witnesses.

GEORGE BIBLE.
